H. M. SHEER

BROODER

Filed Nov. 18, 1922

Henry M. Sheer Inventor
of Vermont E. Hedges
his Attorney

UNITED STATES PATENT OFFICE.

HENRY M. SHEER, OF QUINCY, ILLINOIS.

BROODER.

Application filed November 18, 1922. Serial No. 601,925.

To all whom it may concern:

Be it known that I, HENRY M. SHEER, a citizen of the United States, residing at Quincy, in the county of Adams and State 5 of Illinois, have invented certain new and useful Improvements in Brooders, of which the following is a specification.

My invention relates to an improvement in brooders.

- 10 The present invention provides a convenient arrangement for gaining access to the stove or burner, and it consists in a burner or stove having a smoke-pipe with an elbow or gooseneck in connection with a canopy having an opening through which the smoke-pipe passes, which canopy is adapted to be tilted over on one edge as a support or bearing, away from, and to one side of, the stove or burner, without the necessity 20 of disconnecting or removing the smoke-pipe.

The accompanying drawing is a view in perspective.

A, represents a stove or burner of any 25 approved type; and 1, is a tank for supplying fuel thereto through the pipe 2.

The numeral 3 indicates a canopy of the portable type having a hole 4, through which the smoke-pipe 5 extends loosely.

30 The smoke-pipe 5 is of the gooseneck type, having an elbow 6 adjacent to the stove or burner, a horizontal section 7, and another elbow 8 connecting the horizontal section with the vertical part of the pipe.

35 The size of the opening 4 in the canopy is preferably just large enough to receive the crown flange of the stove or burner, when the canopy is in place over the stove or burner. The canopy may have legs 10 at one side, and the outer end of the smoke-pipe may rest upon supports 11, if desired.

40 These canopies are more or less heavy, and, where the smoke-pipe leads directly up from the stove or burner, it is necessary to lift them bodily, and to facilitate handling them it is customary to use cables and pulleys in order to lift the canopy to the ceiling, if need be. All this I avoid by 45 providing the goose-neck smoke-pipe, which extends off more or less directly to one side of the stove or burner, and running this gooseneck pipe through a hole in the canopy of sufficient size so that when the latter is tilted over on edge, the hole will clear 50 the inner elbow or gooseneck, and at the

same time the canopy will be out of the way, making the burner or stove easily accessible, and without any of the difficulty attendant upon bodily lifting the canopy away from the stove or burner. 60

While the legs 10 are convenient as a support and bearing when the canopy is tilted, and also to prevent its rolling, they are not absolutely necessary and can be omitted altogether, as the canopy can be 65 conveniently tilted to one side, either with or without them, without disturbing the pipe and making it perfectly easy to get at the stove or burner. 70

I claim:

1. The combination of a stove or burner, a gooseneck stove-pipe, and a canopy having a hole of sufficient size through which the pipe extends to admit of the canopy being tilted to one side without disturbing the pipe. 75

2. The combination of a stove or burner, a gooseneck stove-pipe, a canopy having a hole of sufficient size through which the pipe extends to admit of the canopy being 80 tilted to one side without disturbing the pipe, and means for supporting the outer end of the pipe.

3. The combination of a stove or burner, a gooseneck stove-pipe, a canopy having a 85 hole of sufficient size through which the pipe extends to admit of the canopy being tilted to one side without disturbing the pipe, the canopy having legs on one side upon which the canopy is tilted as a support and bearing, and by means of which it is prevented from turning. 90

4. The combination of the canopy with a central opening in the top in connection with the burner which closes the opening 95 when the canopy is normally placed and affords a support for it, and a goose-neck smoke pipe extending through the opening.

5. The combination of a stove or burner, a canopy having an opening in the top 100 adapted to be filled by the top of the burner when the canopy is in its normal position, and a gooseneck pipe extending from the burner through the opening in the canopy whereby to permit the canopy to be tilted 105 to one side while the pipe is still in the opening therein.

In testimony whereof I affix my signature.

HENRY M. SHEER.
